LAST

John Frederick Smith, Quincy, Mass., assignor to
 Compo Shoe Machinery Corporation, Boston,
 Mass., a corporation of Delaware

Application August 26, 1938, Serial No. 226,915

2 Claims. (Cl. 12—133)

This invention relates to the manufacture of cemented footwear in which an adhesive is electrically heated, and more particularly to an electrode equipped last useful in such manufacture.

A process of joining shoe parts with adhesive heated by an energized field created by high-frequency electrical current is described in United States Patent No. 2,087,480 issued to E. C. Pitman on July 20, 1937, and improved apparatus for carrying out such process is described in United States Patent No. 2,109,323 issued to J. F. Smith on February 22, 1938. The present invention concerns a last on which shoes are adapted to be made in accordance with the procedures described in said patents.

A general object of the invention is to provide a last of electrically non-conductive material having conductive portions or surfaces configured and disposed to oppose selected areas of a shoe, and having convenient means for supplying electrical energy to such portions or surfaces.

More particularly, objects of the invention are to provide a last having an electrode which may be in the form of one or more plates, strips or grids positioned adjacent to those parts of a shoe which are to be bonded together, and to provide for supplying energy to all portions of such electrode when the latter is composed of separate parts.

A further object of the invention is to provide a hinged last having an electrode on at least one of its hinged sections and having means for supplying electrical energy to such electrode from another last section.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the claims.

For a fuller understanding of the nature and objects of the invention reference should be had to the following detailed description taken in connection with the accompanying drawing, in which:

Fig. 1 is a side elevation of a last embodying features of the invention, part thereof being broken away better to show the construction;

Fig. 2 is a side elevation of another form of the invention as embodied in a hinged last, parts thereof being broken away;

Fig. 3 is a bottom view of the last shown in Fig. 2; and

Fig. 4 is a transverse sectional view across the forepart portion of the last of Fig. 2.

Referring more particularly to the drawing and first to Fig. 1 there is shown a last 10 of solid or unhinged construction which is provided with improved means enabling it to be used to advantage in shoe cementing processes such as those described in the mentioned Pitman and Smith patents. These processes involve the heating of an adhesive which is placed between electrodes or terminals arranged in the manner of condenser plates in a high frequency oscillating circuit. When the bottom portions of a shoe are to be adhesively bonded in this manner, as for example when the outsole is being cemented to the upper or the upper materials are being cemented, one of these electrodes is placed on the bottom of the last and another on the underlying surface of the pressure diaphragm which is provided in the conventional shoe pressing equipment. As the most intense heat is developed in the dielectric space immediately between the opposed electrodes the area to be treated can be controlled by suitable configuration and disposition of the electrode on the last.

Thus, in Fig. 1 the last 10, which is of electrically non-conductive material such as wood or a suitably molded plastic or the like, has on its bottom an electrode 11 which, as illustrated, may comprise an electrically conductive metallic plate, of copper or other suitable material. These terms "electrically non-conductive" and "electrically conductive" or other terms of similar import as used throughout the present specification and claims are intended to be relative. That is, the shoe last should desirably be made of materials such as wood or others, having a high dielectric strength, which are sufficiently resistant to ordinary currents at ordinary frequencies to be usually regarded as "non-conductive," even though their resistive or insulative effect may be largely reduced or even substantially nullified in a field having the extremely high-frequencies employed in the processes contemplated by the present invention. The electrode is of material having relatively low electrical resistance as compared with the last body, being "conductive" in the sense that it is sufficiently relatively non-resistant to afford a means of localizing and defining the vicinity of the most intensive high frequency field action. This electrode may extend over the entire bottom of the last if full bottom cementing is wanted, or may be limited to selected areas. Usually it is preferable to dispose the electrode around the marginal portions only of the

forepart, and over either the shank margins or the full shank portion, and to avoid the heel area, since most shoes are bottom cemented only in these marginal forepart and shank areas. The heel seat area is preferably avoided because this part of the outsole is usually attached to the upper after a heel seat cutting-on operation, which occurs after the forepart and shank have been cemented. Also the heel of most shoes is tack lasted and the presence of this metal at the heel, if placed in a high frequency field, might engender a harmful amount of heat. The forepart and shank areas, on the other hand, are preferably cement lasted, or stitched, to avoid or reduce the presence of metal in the bonding area. When the shoe has a metal shank stiffener, then the electrode is preferably confined to the side margins of the shank portion of the bottom of the last, so as not to overlap the centrally disposed stiffener.

The electrode 11 instead of being a plate, can be a conductor of any other suitable form, for example, a wire mesh or grid (not shown) or a continuous wire which may be laid sinuously over any desired part of the last. It is fastened directly to the last in any suitable or desired manner as by adhesive, tacks, or screws, and the latter, if used, are countersunk or smoothed so as not to project into the dielectric space between the electrodes. The entire electrode may preferably be coated or faced with a protective covering of lacquer, porcelain, enamel, or the like to prevent accidental formation of such projections through scratching or scarring.

The supply of electrical energy for the heating electrode can conveniently be led to the vicinity of the heel post of the press in which the shoe cementing operation occurs and, as shown in Fig. 1, can be led thence to the electrode. In that figure the shoe press heel post is designated 12 and has at its lower side an electrically conductive plug or jack 13 which may be mounted on the heel post or freely movable with respect thereto as preferred. This plug is in circuit by means of a conduit 14 with one side of the oscillating circuit, which is not illustrated, but which may be set up in any desired manner, for example as shown in my mentioned Patent No. 2,109,323. Plug 13 has a downwardly extending pin 15 which fits snugly into electrical contact with the liner 16 of the conventional jack-pin hole provided in the heel portion of the last. This liner is of conductive metal. An electric conductor is provided between liner 16 and electrode 11 and may preferably take the form of a metallic pin or rivet 17.

Instead of leading the electric energy through the jack-pin hole it may be otherwise brought to the electrode, for example by a direct outside wire, but the described arrangement is much more convenient and lends itself readily to use in conjunction with existing types of shoe presses and lasts. When the current is led directly to the jack or plug 13 beneath heel post 12 care must of course be taken that such post is suitably insulated with respect to the remainder of the circuit, which can be done by making the entire post of non-conductive material or by putting an insulating facing 18 on its under side.

In Figs. 2 and 4 means are shown for providing a hinged last with an electrode having different portions on different last sections, and with means for supplying energy to all of these electrode portions. Here the last 110 comprises a forepart section 19 and a heel section 20, which

are hinged about the pivot 21 for movement between broken and unbroken positions.

An electrode 111 is provided on the under side of the last and may preferably, as illustrated, be of loop configuration extending around the marginal forepart and shank portions of the last bottom. The electrode is made in different portions corresponding with the different last sections, there being a forepart portion 22 and a rear or heel portion 23 respectively provided with means for making contact with each other when the last is in unbroken condition. As best shown in Fig. 2, the electrode portion 22 has flanges 24 extending upwardly into the hinge joint opposite corresponding flanges 25 on opposed parts of the cone electrode portion 23. While these flanges may separate when the last is in broken condition, they will always be in firm abutting contact when the last is in operative unbroken condition within a shoe, and if desired may be given a slight spring toward each other if the metal employed is amenable to tempering.

The electrical energy is conveniently supplied to electrode portion 23 through a conductive jack-pin hole liner 116 and a conducting pin or rivet 117, the lower end of which is anchored in a centrally disposed rearwardly extending tongue 26 on the electrode portion 23.

The electrode proper terminates approximately at the heel breast line designated 27, thus leaving the entire heel seat area, except for the part adjacent tongue 26, uncovered by the electrode. A tack clenching plate 28 can be positioned around the marginal heel portion of the last bottom and is spaced or remote from the electrode. This clenching plate does not partake of the heating functions of the electrode circuit and has no current therein save what possibly might be induced from the presence of the field about the electrode, but the clenching plate is sufficiently remote to avoid any harmful heating at the tacked heel end of the shoe. A similar clenching plate 28 may be exposed on the bottom of the form of last shown in Fig. 1 and is similarly spaced or insulated from the electrode circuit.

Current may be led to the electrode 111 by means of a conductive heel post such as that shown in the Smith Patent 2,109,323 which as shown in Fig. 2 herein may comprise a block 29 of insulating material with a metallic contact plate 30 therebeneath in circuit with a conductive bolt 31 to which high frequency electrical energy is supplied. The top of the last can be provided with an electrical conductive contact plate 32 abutting plate 30 and contacting liner 116. Preferably the last of Fig. 1 may also be provided with such a contact plate 32, thus adapting it more readily for use with a press having a contact plate type of heel post.

Various changes and departures from the illustrated embodiments of the invention may be made without departing from its principles. Thus the circuit to or between different electrode portions such as 22 and 23, while conveniently effected by means of abutting flanges, may be maintained in other ways as, for example, by separate wiring for each portion. Such wiring, for example, could lead from one electrode section thru the last hinge pin to another section. It will also be appreciated that the electrode can be made in any desired configuration and can be disposed on any part of the last adjacent which it is desired to set up a heating field. Thus the electrode could be disposed about the toe of the

last for cooperation with another outside electrode for the purpose of heating box toes to dry them or to aid in molding them if they are of thermoplastic material. The heating field set up adjacent the electrode may be employed in cementing operations, either to fuse or make tacky a thermoplastic adhesive or to drive off solvent so as to speed the setting of an adhesive such as pyroxylin cement.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A last for use in a shoemaking process wherein shoe parts are stuck together with an adhesive heated by a high frequency electrical field, comprising a last body of electrically non-conductive material, a U-shaped metal clenching plate extending around the entire marginal heel seat portion of said last, but not over the central

5 heel seat portion thereof, a metal electrode plate on the forepart and shank portions of said last bottom having a rearwardly extending tongue underlying the central heel seat portion of said last, said electrode plate and tongue being spaced from said clenching plate so as to be electrically insulated with respect thereto, said last having a jack-pin hole, and an electric conductor extending from said hole to said tongue through a passage forming an aligned continuation of the jack-pin hole.

10 2. A last for use in a shoemaking process wherein parts of shoes having a tack or staple lasted heel seat are stuck together with an adhesive heated by a high frequency electrical field, comprising a last body of electrically non-conductive material having a jack-pin hole, a metal high frequency electrode on the forepart and shank portions of said last bottom, the marginal 15 portions of which terminate rearwardly approximately at the heel breast line, said electrode having a rearwardly extending centrally disposed tongue underlying said jack-pin hole but clearing the marginal lasting edge of the heel seat of said last, there being a passage forming a continuation of 20 said hole extending to the last bottom, and electrical conductor in said passage connecting said tongue with the interior of said hole for access to a source of high frequency current.

JOHN FREDERICK SMITH.
